UNITED STATES PATENT OFFICE.

MARTIN C. SCHWAB, OF CHICAGO, ILLINOIS.

SIGNAL FOR ELEVATORS.

1,052,285.

Specification of Letters Patent.

Patented Feb. 4, 1913.

Application filed December 8, 1910. Serial No. 596,229.

To all whom it may concern.

Be it known that I, MARTIN C. SCHWAB, a citizen of the United States, residing at Chicago, in the county of Cook and State of Illinois, have invented certain new and useful Improvements in Signals for Elevators, of which the following is a specification.

The present invention relates to a system by which a person standing upon any floor 10 of a building may signal the operator of the next approaching car, going up or down, to stop when the floor from which signal is given is reached. Signals for this purpose have heretofore been used, but in all cases of 15 which I am aware the signal given the operator is of either the audible or visible type, or both, as for example either a bell, a light or a target, or two or more of them. But signals of these types are open to the 20 objection that they are not always seen or heard by the attendants and frequently do not make a sufficient impression upon the attendant to attract his attention and call him to his duty. This may be because they 25 occur so frequently that the operator becomes oblivious to them, especially if his attention is absorbed by others about him. Frequent instances of this can be seen any 30 day in any modern building equipped with an elevator system, and as a result of it the attendant frequently runs past his floor so that he must stop and return to take on a passenger. This entails a very material 35 waste in the running expense, to say nothing of the delay and annoyance occasioned passengers, and the saving of this waste and avoiding of this delay and annoyance are among the principal objects of the present 40 invention, and the object originally aimed at. The object of the invention is to provide a 45 signaling system by which these objections are obviated and to this end the improved signal is so constructed that it will manifest itself to the attendant through the sense of touch either alone or also in connection with the sense of sight or hearing or both. This 50 objection is obviated and in addition thereto, material advantages are attained by the use of a signal constructed according to the present invention, such a signal being more 55 positive and efficient in its action than a signal which manifests itself to the attendant through the sense of sight or the sense of hearing or both. To this end the handle 60 of the controller of an elevator car is made a part of the signal. Or, in other words,

the controller has a combined signal and handle which is gripped by the operator so that upon the receiving of the signal no time is lost in finding and grasping the 60 handle. The signal is given to the operator by exciting the handle in a manner which is perceptible through the sense of touch and so far as I am aware such a combined handle and signal is entirely new. The handle may also be excited, if desired, in a manner which is also perceptible by the sense of hearing and the exciting may be done by any of a number of devices variously constructed to meet individual requirements. 65 It may be done by causing its physical vibration or by causing an electric current to pass through it and into the hand of the operator and in either event it is essentially what may be called a "touch signal" 70 which is not necessarily either a visible signal or an audible signal. It may, however, be made audible as well as perceptible through the sense of touch, by making the means for exciting it of such construction 75 that its operation produces a sound resembling that of a buzzer or the rapid tapping of a hammer on a resonant body, and this sound when produced at or within the handle will more surely attract the attention of 80 the attendant than if produced at a distance. This placing of the signal, whatever its character or construction may be, directly at or within the handle of the controller, or making them one and the same part having 85 the functions of both a handle and a signal, is another important feature of the invention.

The invention consists in the features of novelty that are hereinafter described with 90 reference to the accompanying drawings, which are made a part of this specification and in which:

Figure 1 is a diagrammatic view of an 95 elevator system, comprising three elevator cars, equipped with the improved signal and adapted to run past any desired number of floors, although only three floors are shown equipped. Fig. 1^a is a detail view of one of the switches, modified. Figs. 2 and 3 are 100 details of the traveling contact of one car and the fixed contacts of two of the signal circuits appropriate to one car and one of the floors. Fig. 4 is a diagrammatic view of 105 single elevator car equipped with a touch signal embodying the generic invention and adapted to operate automatically at fixed 110

points. Figs. 5, 6 and 7 are details of the trip mechanism for operating the switch of the signal circuit. Figs. 8 and 9 are detail views of body-pieces under three different 5 modifications all adapted for use in the improved signal.

Since the original aim of the invention was to produce a more effective signal for use in connection with elevators, this embodiment of it will be described. It contemplates a signaling system by which a signal perceptible through the sense of touch is given to the operator as he is about to reach the floor at which the signal indicated he is to stop the car. In carrying out 10 this idea a pair of switches or push buttons, as they are hereinafter called, one "up" and one "down," is located at each floor of the building and each of said buttons is included in a separate control circuit which 15 controls the open or closed condition of a switch in one of an equal number of signal circuits. All of these signal circuits include all of a number of so-called touch signals, 20 one carried by each car. Each of said signal circuits has two fixed terminal contacts appropriate to each floor of the building (one "up" and the other "down") and a single movable contact appropriate to and moved 25 by each car, said movable contact being adapted to travel in unison with the car, so that whenever a movable contact engages a fixed contact and closes the signal circuit at this point, if it was previously closed at 30 its switch by the closing of the control circuit, the touch signal will be given the attendant through the body piece handle of the controller.

The system as shown in Fig. 1 of the drawings has three cars, 1, 2 and 3, each adapted 40 to reciprocate in a separate shaft by suitable power mechanism (not shown) although it will be understood that the invention is applicable to a system having a greater or less number of cars. The drawings also show but three floors of a building 45 equipped to be served by the improved signaling system, but it will be understood that any number of floors may be similarly equipped by simply duplicating the parts 50 peculiar to any one floor as shown, it being understood that however many floors are to be equipped no provision is made for the top and bottom floors. It is to be understood, therefore, that the drawing is simply 55 illustrative and that the capacity of the system either as to the number of cars or number of floors may be made to meet requirements.

60 Located at a convenient point on each floor is a pair of switches, which, for the sake of distinction, are herein called push buttons, one of which, 4, is to be pushed to close a control circuit, 5, when it is desired to signal a car going up to stop, and the

other of which push buttons, 6, is to be pushed to close a control circuit 7 when it is desired to signal a car going down to stop. The control circuit 5 leads through the coil of an electromagnet 8 thence through 70 a wire 9 to one end of a bus-bar 10, thence through a wire 11 to the positive pole of a battery, 12, or other source of electricity, and thence from the negative pole of the battery through a wire, 13, back to the push button. The other control circuit, 7, leads through 75 the coil of an electromagnet, 14, and thence back to the push button, 6, through precisely the same course as just described.

The magnets, 8 and 14, when energized, 80 attract pendant armatures, 15 and 16, respectively, which are normally in operative proximity to the magnets and have suspended from them double acting tappets, 17 and 18, respectively, which are adapted 85 to engage oscillatory switches, 19 and 20, respectively, for oscillating them in one direction or the other for opening or closing, as the case may be, the signal circuit. Each of these switches consists of a three-armed part 90 pivotally mounted at the intersection of its arms, one of which arms extends upward so that its upper end is in position to be engaged by the tappet when moved in either direction. The upwardly extending arm is 95 movable equal distances from its central position—directly over the pivotal center, and it is preferably weighted so that when thrown by the tappet back and forth past the center the preponderance of weight will 100 be at the side of the center where it will remain and hold the switch while allowing the tappet to gravitate to its normal, central position. The other two arms of the switch extend downward from the pivoted axis, and 105 are of unequal lengths. One of them constantly and at all times dips into a body of mercury contained in cup, 22, but when the electromagnet, 8, (or 14) is energized its armature is attracted, the tappet thrown over, the switch oscillated, and its short arm submerged in the mercury in the cup 22 (or 24) without withdrawing its longer arm from the mercury in the cup 21 (or 23). These mercury cups and switches form parts 110 of signal circuits, 25 and 26, which include the coils of electromagnets, 27 and 28, respectively. Here it should be observed that these signal circuits are common to all of the signals on all of the cars, since, under 115 proper conditions, any of them will operate the signal on any of the cars. They are arranged in pairs (25—25, 25^a—26^a, 25^b—26^b) and the pairs are connected with separate insulated plates, 30, 30^a and 30^b, respectively, 120 located at about the mid-height of the elevator shaft, this plate being, in turn, connected by looped wires, 31, 32 and 33 with the touch signals, 34, 35 and 36, respectively, of the cars 1, 2 and 3. In turn all of the 125 130

signals, 34, 35 and 36 are connected by looped wires, 37, 38 and 39 with a plate, 40, located at mid-height of the elevator shaft which plate is in turn connected with the return wire, 13, of the battery circuits.

Each of the signal circuits, is common to all of the push buttons of a given name, or rather to the direction of travel of any car. For example, the circuit 25 is common to all of the cars when going upward, while the circuit, 26, is common to all of the cars when going downward, and this is brought about by the following arrangement: The cars 1, 2 and 3 are respectively connected with worms 41, 42 and 43, so that the worms rotate in unison with the travel of the cars. Each worm carries a nut, 44, 45 and 46, which feeds along the worm as it rotates so that the position of the nut on the worm 20 at all times corresponds with the position of the car in its shaft. Each nut is provided on one side with a pair of fingers, 47, which straddle the bus bar, 10, 10^a and 10^b of the respective cars, whereby the nut 25 is prevented from turning, but permitted it to be oscillated by frictional contact with its worm so that one of its fingers is at all times in electrical contact with the corresponding bus bar. Projecting from the opposite side of the nut is a finger, 48, which forms a traveling contact adapted to engage one or the other of a pair of fixed contacts, 49 or 50, accordingly as the finger or traveling contact is in its upper or lower 30 position, and this position of the traveling contact is determined by the direction of rotation of the worm, which, in turn, is determined by the direction of travel of the car.

Located in the path of the nut of each car 40 are as many contacts 49 49^a, etc., and as many contacts 50 50^a, etc., as there are floors at which push buttons 4 and 6 are located. All of the contacts 49, etc., appropriate to each floor are electrically connected, as by a 45 metallic bar 51, which is electrically connected to the signal circuit, 25, and all of the contacts 50 are similarly mounted and electrically connected by a bar 52 with the signal circuit, 26, and there are as many of 50 these contacts 49, etc., and 50, etc., located in the travel of each nut as there are floors. Thus, as shown in the drawing, there are three contacts 49, etc., within the path of 55 and adapted to be engaged by each of the traveling contacts, 48, as the car is going up, and three of the contacts 50, etc., within the path and adapted to be engaged by the traveling contact 48 as the car is going down.

60 The operation of the system so far described is as follows: Let it be assumed that cars 1 and 2 are going down and car 3 is going up, with the nuts in the positions shown, and that one passenger on the middle floor desires to go down and another

passenger on the same floor desires to go up. The down passenger pushes the down button 6^a and this energizes the electromagnet 14^a, closes the circuit 26^a at 20^a and upon releasing the button allows the armature 16^a 70 and tappet 17^a to return by gravity to normal positions leaving the signal circuit 26^a closed at 20^a but open at 50^a. The up passenger pushes the up button 4^a which in like manner energizes the magnet 8^a and closes the signal circuit 25^a and 19^a, leaving it open at 49^a. These operations do not energize any of the magnets excepting 8^a and 14^a and do not close any of the signal circuits at their switches excepting 25^a and 26^a, all 75 of which are appropriate to the middle floor, and leaves these open at 49^a and 50^a, to be closed by whichever of the traveling contacts 48 first reaches and contacts with them. For example, it has been assumed that cars 1 and 2 are above the middle floor and going down. Their contacts 48 are set for engagement with contacts 50, 50^a and 50^b, and whichever of the contacts 48 reaches a contact 50^a first, whether it be the contact 90 of the car 1 or of the car 2, all of the contacts 50^a being electrically connected with each other, will close the signal circuit 26^a at this point. This will send an instantaneous impulse through the signal on the car, 95 and will at the same time energize the electromagnet 28^a and thus attract its armature 16^a, move the tappet 17^a, shift the switch 20^a to normal position and again open the signal circuit. Hence as the next car is descending its contact 48 will also engage the contact 50^a and close the circuit 26^a at this point, but as it is open at the switch 20^a, no effect will be produced. In like manner, the signal circuit 25^a was closed at the 100 switch 19^a by the push button 4^a so that, as the car 3 ascends, its traveling contact 48 will engage the contact 49^a and close the signal circuit 25^a with like results.

It will be observed that a car going in one direction can not close a signal circuit which is set to be operated by a car going in the opposite direction, and that all contacts of a like character appropriate to each floor are common to all of the cars, so that the pushing of a button on any floor will set the signal which will be picked up by the first car going in the right direction, which reaches it. It will be observed also that the signaling impulse will be momentary 110 because the passing of the current instantly energizes the electromagnet (27^a or 28^a) which is included in it and breaks the circuit by shifting the oscillating switch which 115 also is included in it.

The signal proper may be of any desired construction and location so long as it is in physical touch with the hand of the attendant at all times when it is apt to be set in operation, and when it operates will 120 125 130

manifest itself to the attendant through the sense of touch or touch and sound. For example in Fig. 8 it is shown as consisting of magneto electromechanism, 53, such as is used in an ordinary call-bell, or buzzer, contained within the hollow handle, 34, of the elevator controller, 54, the hammer, 55, being arranged to strike against the inside of the hollow handle. With this arrangement when the circuit signal, 31, 37 is closed the hammer will be caused to rapidly strike against the handle and produce rapid physical shocks or vibrations which are perceptible to the touch of the attendant so long as he keeps his hand upon the handle, and will also produce a sound. The handle may be of wood, metal or any other material capable of being disturbed or excited in such manner that its disturbance is perceptible through the sense of touch. Its disturbance or excitement may, however, be electrical. As shown in Fig. 9, the handle consists of two insulated metallic semicylindrical pieces, 56, which, together, form the hollow grip or handle of the controller lever, 57, which pieces form the terminals of the secondary circuit, 58^a, of an induction coil, 58, the main circuit of which is included in the signal circuit, 31, 37. When the signal circuit is energized the hand of the attendant, in gripping the two pieces, 56, will complete the secondary circuit of the induction coil and the attendant will receive an electric shock, which will be only momentary as already explained. The main circuit of the induction coil may include a make and break 59 in which case the armature will act after the manner of a buzzer and also as a hammer and thus cause signals of three different characters, *i. e.*, both electrical and mechanical vibrations of the handle, both of which are perceptible through the sense of touch and a buzzing or rattling sound perceptible through the sense of hearing.

Figs. 4 to 7, inclusive, represent the adaptation of the improved signaling system to a single elevator car which is intended to be run between fixed limits either with or without stopping at intermediate points. For example, most elevators used in buildings are provided with top and bottom limit stops which automatically stop the car, but where these automatic limit stops are not used the improved signaling apparatus may be used to attract the attention of the attendant, thus calling upon him to stop the car before it passes its normal limit and damages the machinery. Again, in mine elevators and construction hoists it is sometimes desirable to run the car between two given levels of the mine or building in course of construction. The mechanism shown in Figs. 4 to 7 is adapted for this use. As

here shown, the car carries a projecting finger, 62, which, as the car is about to reach its top or bottom limit momentarily closes the signal circuit and produces a signal in the handle, 34, of the controller. As the car proceeds from the position shown the finger will engage a tappet, 63, which is mounted so as to be capable of turning on a shaft, 64, and this tappet carries a pin, 65, which occupies a curved slot, 66, in the adjacent face of a rocker 75 which is also loosely mounted upon the shaft 64, and has diametrically projecting vertical arms, 67, from the lower one of which is suspended a weight, 68, which holds the rocker in its normal position. Normally 80 the pin, 65, is at the bottom of the slot, 66, so that when the tappet, 63, is forced downward the rocker will be moved about the shaft as a pivot and will, by the weight, be restored to normal position, as soon as the finger, 62, escapes past the tappet, 63. The movement of the rocker away from its normal position will move a thrust bar, 69, the end of which is jointed to the upper end of a three armed oscillating switch, 70, and the switch will be oscillated in such manner that it will close the signal circuit, 71, in the manner and with the results already described with reference to Fig. 1. This closing of the circuit will be momentary and the circuit will again be opened when the finger, 62, passes the tappet, 63, by reason of the fact that the weight, 68, will then instantly break the circuit and restore the rocker to the position shown. If, now, the car be 100 started upward the finger, 62, will engage the under side of the tappet, 63, and the curved slot, 66, will permit the pin to move upward without turning the rocker. When the car is about to reach its top limit the finger, 62, will engage a tappet, 71, which is loosely mounted upon a shaft, 72, and through the medium of a pin, 73, which occupies a curved slot, 74, in the adjacent face of a rocker, 75, turns the rocker in the manner already described with the result that the switch, 76, of the signal circuit, 77, will be closed in the manner already described. Here, again, as soon as the finger passes the tappet, 71, the circuit will be again opened 115 by the weight, 68. As the car then travels down the finger, 62, will engage the tappet, 71, and the slot, 74, will permit the tappet, to be depressed without moving the rocker, 75. Thereafter, as soon as the finger escapes 120 from the tappet the tappet will be lifted to its normal position by a spring, 78.

The mechanism for raising and lowering the elevator cars is not shown in the drawing for the reason that it forms no part of 125 the present invention and any desired mechanism for this purpose may be used in connection with the invention.

What I claim as new and desire to secure by Letters Patent is:

1. The combination with an elevator car and a controller therefor, said controller having a handle, of means carried by the handle for exciting it in a manner which is perceptible through the sense of touch, and means for operating said exciting means.

2. The combination with an elevator car and a controller therefor, said controller having a handle, of means carried by the handle for exciting it in a manner which is perceptible through the sense of touch and

also through the sense of hearing, and means for operating said exciting means. 15

3. The combination with an elevator car and a controller therefor, said controller having a combined handle and signal, of means for exciting said handle in a manner perceptible through the sense of touch and 20 also causing it to produce a sound.
